FIRE EXTINGUISHER

Charles H. Lindsay, Elmira, N. Y., assignor to
American-La France-Foamite Corporation, El-
mira, N. Y., a corporation of New York

Application April 9, 1937, Serial No. 135,837

6 Claims. (Cl. 169—31)

The invention relates to fire extinguishers in which a liquid, usually one of low freezing point, is expelled from a container by gas pressure released therein at the time of discharge, such gas being normally stored within the container in a capsule or flask. The invention relates more directly to such extinguishers, in which the act of inversion of the container operates to cause the puncturing of the sealing disc of the gas flask, thus to release the pressure, and the object, among other things, is to improve on this class of extinguisher and particularly to compensate for pressure variations incident to extremes of temperature.

15 In the accompanying drawing,

Fig. 1 represents an extinguisher of the type referred to in inverted position and partly broken out to show the interior.

20 Fig. 2 is a section of the flask and its mounting. Figs. 3 and 4 are respectively sections on lines III—III and IV—IV of Figs. 5 and 6, and

Figs. 5 and 6 are details of the puncturing mechanism in the form at present preferred.

The container marked 1 is provided with an 25 outlet hose 2 and a screw closure cap 3, by which it can be set on its head when inverted and in action. The cap has a central anvil 4 against which it can be bumped on the floor or ground, to produce or insure operation. The container 1 30 may be assumed to contain an appropriate quantity of any liquid, a solution of calcium chloride, for example.

The gas flask 5 contains liquid carbon dioxide, 35 normally confined therein by a rupturable disc 6, which is clamped to and within the tubular head 7 of the flask by means of a tubular clamp plug 8. The bore through the plug and flask head is continued to near the opposite end of the flask (upper in the drawing) by means of a dip tube 9, the function of which will be presently explained.

40 Thus organized, the flask is screwed or otherwise attached to a carriage 10 mounted on a fixed post 11 which may be an integral part of the screw cap, as shown, although the form of carriage mounting is subject to variation, according to preference. The carriage and hence the flask, are adapted to slide back and forth on the post 11 being confined thereon by a washer 12.

The sealing disc 6 is intended to be punctured 45 by the punch or piercer 13, which is threaded or otherwise fastened to the guide post 11. The blade portion of the punch is formed of two diameters, the free end or head 14 being larger than its shank part 15 and also desirably bevelled or sharpened, or otherwise shaped, to make an

easy cut of the disc, folding back the cut flap, as it passes the disc.

In the erect position of the extinguisher the flask and its carriage hang from the washer 12 and the head 14 of the punch then occupies the bore in the clamp plug 8 in about the relation indicated in Fig. 2 which shows the parts at the instant of inversion and before the flask has started to move. When the extinguisher is inverted and bumped on the floor the impact causes the flask to slide on its post relatively to the punch and the latter punctures the disc, the parts then assuming the relative position shown in Fig. 5. The disc being thus opened, the confined gas rushes out of the flask around the punch and through the carriage ports 16 into the container where its action on the liquid expels it through the hose. If the pressure of the gas in the flask is high, as it will be when the temperature is normal, say 70° F. or above, the reaction of the 20 escaping gas will cause the flask to recoil or blow back upwards to its original position limited by the washer 12, in which case the head 14 of the punch will occupy the part 17 of the bore in the clamp plug 8. If, however, the flask pressure 25 is low, due to abnormal low temperature, say zero or below, or other cause, the gas reaction or recoil will not be sufficient to lift the weight of the flask and it will therefore remain in the position to which it fell, in which the head 14 occupies the part 18 of the discharge bore, this being the part that is within the flask head 7.

The bore 17 is smaller than the bore 18, and therefore in the case of high flask pressure (recoiled flask) the escape path for the gas is relatively restricted, whereas in the case of lower pressure it is relatively larger. The dimensions of the bore and the punch head diameters are mutually calibrated with reference to the size or weight of the flask and its associated parts so 40 as to take care of the two extremes of temperature, as just described. The result of this automatic control is that an adequate pressure, sufficient to expel the extinguisher liquid with a proper stream range is instantly established even 45 when the carbon dioxide in the flask is very cold, and yet is not excessive at higher or normal temperature say 70° F. or above and a practically constant pressure is maintained in the container throughout the discharge period.

50 The dip tube 9 contributes to the proper action. In the inverted or operating position it reaches up above the level of the liquid carbon dioxide and therefore delivers gas only into the discharge bore. The gas so delivered, it will be 55

understood is derived from the vaporizing liquid which, at a given temperature, will vaporize only as fast as the previously vaporized gas can escape through the narrow bore, in consequence of which the pressure admitted to the container will be properly controlled by the calibration; except for this fact liquefied carbon dioxide would flow directly through the calibrated passages with an excessive gas development and an irregular and undesirable action. The dip tube also minimizes the possibility of rust or scale in the flask falling into and clogging the calibrated outlet and avoids the use or need of screens for this purpose.

It may be noted that the functioning of the extinguisher in the manner described is essentially the result of the relative movement of the flask and piercer, no matter how brought about, and the mutual calibration of the piercer and the discharge bore whereby the effect of gas reaction is to place the parts in the flow-restricting position whereas if there is no gas reaction, the parts remain in the position to which they were brought by the force of puncturing the disc. It will be obvious that the calibrated discharge bore may be formed in the flask head structure or otherwise as preferred.

I claim:

1. In an extinguisher, the combination of a container for liquid to be expelled, a disc-sealed flask of liquid carbon dioxide movable therein between two limits of position and having a discharge bore of predetermined dimension, a relatively fixed piercer adapted to operate in said bore and against which the flask may fall to puncture its sealing disc, said piercer and bore being mutually calibrated to provide a smaller gas escape path when the bore is in its position farthest removed from said piercer than when nearest thereto.
2. In an extinguisher, the combination of a container for liquid to be expelled, a disc-sealed flask of liquid carbon dioxide having a discharge bore of predetermined dimension, a piercer adapted to occupy said bore, said flask being relatively movable with respect to said piercer in one direction by a force adapted to puncture said disc and in the other by the reaction of the escaping gas, said bore and piercer being mutually calibrated to provide a smaller gas escape path in the

relative position of said parts produced by gas reaction than in the position produced by said other force.

3. In an extinguisher, the combination of a container for liquid to be expelled, a disc-sealed flask of liquid carbon dioxide having a discharge bore of predetermined dimension, a piercer in said bore adapted to puncture the disc, said flask being relatively movable with respect to said piercer in one direction by a force adapted to puncture the disc, and in the other direction, by the reaction of the escaping gas, said flask having a discharge outlet arranged to discharge gas only through said bore and said bore and piercer being mutually calibrated to provide a smaller gas-escape path through the bore on the gas-reaction position of said parts.

4. In fire extinguishing apparatus, the combination with a movably mounted flask containing liquid carbon dioxide having a discharge outlet and means operated by flask recoil for governing the size of said outlet, said means providing maximum discharge cross area at minimum temperature.

5. In fire extinguishing apparatus, the combination with a disc-sealed flask containing liquid carbon dioxide, the disc being clamped over an outlet bore in the flask head by a disc clamp which has a continuation bore of smaller cross area, of a piercer having an enlargement adapted to occupy either bore.

6. In an extinguisher, the combination of a flask of liquid carbon dioxide having a gas outlet member, a member adapted to occupy said outlet member, said second-named member being relatively movable with respect to said outlet member and mutually calibrated therewith to provide a greater degree of restriction to gas flow through said outlet member in one relative position of said members than in another, one of said members being normally subject to a constant force tending to establish the least degree of restriction and also to the opposing kinetic force of the discharging gas tending to move it to its position establishing the greater degree of restriction, and releasable means for normally confining the gas under pressure in said flask.

CHARLES H. LINDSAY.
